UNITED STATES PATENT OFFICE.

EDWIN F. BEUGLER, OF BUFFALO, NEW YORK, ASSIGNOR TO E. & B. HOLMES MACHINERY CO., OF BUFFALO, NEW YORK, A CORPORATION OF NEW YORK.

COMPRESSOR-JAW MOUNTING FOR BARREL MACHINES.

Application filed October 5, 1922, Serial No. 592,456. Renewed September 27, 1924.

To all whom it may concern:

Be it known that I, EDWIN F. BEUGLER, a citizen of the United States, residing at Buffalo, in the county of Erie and State of New York, have invented new and useful Improvements in Compressor-Jaw Mountings for Barrel Machines, of which the following is a specification.

This invention relates generally to improvements in barrel making machines, but more particularly to the means for mounting the stave-compressing jaws.

In barrel making machines of the type shown in my United States Letters Patent No. 941,404, dated November 30, 1909, the staves are compressed at their upper ends through the medium of a pair of horizontally-swinging compressor arms which are adapted to surround the staves and on which are mounted a series of segmental jaws or plates arranged to contact with the staves when the compressor arms are closed.

The principal object of the invention is to improve the means for yieldingly mounting the segmental jaws on the compressor arms whereby said jaws may be renewed or replaced when necessary without affecting or disturbing their mounting proper.

A further object is to provide a simple and inexpensive mounting of this character which is reliable and durable in construction and not liable to get out of order.

In the accompanying drawings:

Figure 1 is a fragmentary plan view of a pair of compressor arms and associated parts and showing my improvement applied thereto. Figure 2 is an enlarged transverse vertical section on line 2—2, Fig. 1. Figure 3 is a vertical section on line 3—3, Fig. 2. Figure 4 is a fragmentary side view of the mounting. Figure 5 is a perspective view of the fulcrum post or block thereof.

Similar characters of reference indicate corresponding parts throughout the several views.

By way of example, the improved mounting is shown in connection with a machine constructed in accordance with my prior aforesaid patent, but it will be understood that the invention is equally applicable to other machines of this general character.

Referring now to Fig. 1 of the drawings, the numeral 10 indicates the horizontally-swinging compressor arms which are car-

ried by bifurcated yokes 11 fulcrumed on a vertical post 12. The straight portions of these arms are connected by toggle links 13, 14 which are pivoted to each other by a vertical pin 15 guided for movement in a slot 16 formed in an extension member 17 secured to said post 12. Power-actuated mechanism, not shown, is employed for spreading the toggles to contract the compressor arms around the barrel while a coil spring 18 connecting the inner ends of said arms serves to automatically return them to their open or normal position upon the release of the toggle device. The mechanism thus far described forms no part of the present invention and has just been briefly described for the purpose of enabling those skilled in the art to understand the application of the present invention thereto.

As is customary in machines of this type, the compressor arms do not themselves touch the barrel, but each one has a series of segmental jaws or plates 19 thereon which come directly in contact with the barrel staves when the compressor arms are closed. Each of the latter is provided with an equal number of such jaws which are uniformly spaced, each jaw being curved to a circle which is substantially the same radius as the body of the barrel being operated upon. These jaws are yieldingly mounted on the compressor arms so that they are permitted a certain range of movement to adapt them to the irregularities in the shape of the barrels. The preferred means for thus mounting each of these jaws on the respective compressor arms are constructed as follows:

20 indicates a radially-movable slide or carrier plate guided in a dovetail way or groove 21 formed in the upper side of the compressor arm and in an outwardly projecting extension 22 having a depending portion or bracket 23. The segmental jaw is adjustably mounted on this slide and is provided with a laterally extending lug 24 having a slot 25 through which a bolt 26 secured to said slide is adapted to pass. To reliably interlock the jaw with its slide and prevent longitudinal displacement thereof on the latter after being set in an adjusted position, the contiguous faces of said parts are provided with teeth 27. By loosening the nut 28 and shifting the jaw in one direction or the other, the same can be easily

adjusted to suit barrels of different sizes within certain limits.

The jaw-slide 20 is held yieldingly against outward movement relatively to its compressor arm by means of an upright fulcrum member or bar 29 fitted within a recess or socket 30 formed in the depending bracket 23, the upper end of said member projecting into an opening 31 in the outer end of the 5 slide and the lower end of the same engaging outwardly facing bearing surfaces on this socket. Extending diagonally through an opening 32 in this fulcrum bar and through a vertical slot 33 in said bracket is 10 a bolt 34, and applied to the inner end of the latter is a coil spring 35. This spring bears at one end against the bracket and at its other end against a washer 36 and nut 37 so as to constantly resist the outward 15 movement of the jaw-slide.

When the compressor arms are closed around the barrel to compress the staves, the jaws 19 yield more or less to adapt themselves to the slight unevenness and irregularities in the shape of the barrel. The 20 outward movement of each jaw slide 20 is transmitted to its cushioning bar 29 which is free to rock about its lower end as a fulcrum, the spring 35 restraining such movement and automatically returning said slide 25 to its initial position.

For operating upon barrels of different sizes, it is only necessary to substitute jaws of different sizes without in any way affecting 30 the mounting itself.

This improved mounting comprises but few parts which are so constructed and organized that they are not liable to get out of order and which may be readily replaced 35 when desired without the necessity of substituting a whole new mounting.

I claim as my invention:

1. In a machine of the character described, the combination with a pair of compressor 40 arms arranged to encircle a barrel, of a radially movable jaw mounted on each of said arms, and a member fulcrumed on the respective compressor arm and operatively connected to said jaw for yieldingly resisting 45 its movement in one direction.

2. In a machine of the character described, the combination with a pair of compressor

arms arranged to encircle a barrel, of a radially movable slide mounted on each of said arms, a segmental jaw carried by said slide, a fulcrum member supported on the respective compressor arm and operatively connected to said slide, and means for restraining the rocking movement of said member in one direction. 55

3. In a machine of the character described, the combination with a pair of compressor arms arranged to encircle a barrel and each having a bracket, of a radially movable slide mounted on each of said arms and having an opening therein, a segmental jaw carried by said slide, and a yieldable fulcrum member carried by said bracket and engaging the opening in said slide. 60

4. In a machine of the character described, the combination with a pair of compressor arms arranged to encircle a barrel and each having a bracket, of a radially movable slide mounted on each of said arms, a segmental jaw carried by said slide, a yieldable fulcrum member carried by said bracket and operatively connected to said slide, a bolt applied to said member and extending through said bracket, and a coil spring applied to said bolt and bearing against said 70 bracket. 75

5. A machine of the character described, comprising an arm movable toward and from the barrel and provided with a guideway, a bracket depending from the outer side of said arm and having a bearing surface on its lower part and a guide opening on its upper part, a slide movable in said guideway and provided at its inner end with a jaw adapted to engage the barrel and at its outer end with a vertical opening, an upright fulcrum bar engaging its lower end with said bearing surface and its upper end with said opening in the slide and provided between its ends with an opening, a tension bolt passing through the openings of said bracket and fulcrum bar and having a head at its outer end engaging the outer side of said bar, and a spring surrounding the bolt and engaging its outer end with the bracket and operatively connected at its inner end with said bolt. 90

EDWIN F. BEUGLER.
